UNITED STATES PATENT OFFICE.

HARRY A. GOULD, OF ST. LOUIS, MISSOURI.

TOY PISTOL.

1,100,728.

Specification of Letters Patent. Patented June 23, 1914.

Application filed August 13, 1913. Serial No. 784,579.

To all whom it may concern:

Be it known that I, HARRY A. GOULD, citizen of the United States, residing at St. Louis, State of Missouri, have invented 5 certain new and useful Improvements in Toy Pistols, of which the following is a specification.

This invention relates to toys and more particularly to toy pistols embodying a 10 spring actuated throwing or projecting member, the operation of which is controlled by a trigger.

The primary object of this invention is the provision of a toy pistol as specified 15 which is exceedingly simple in construction, durable, and efficient in its operation; being designed for the purpose of throwing a ball or like article into the air.

Another object of this invention is the 20 provision of a basket like structure which is mounted upon the end of the barrel of the pistol so as to receive the ball or like article when the same descends after having been thrown in the air.

25 With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the 35 several views and in which,

Figure 1 is a side elevation of the improved toy pistol, Fig. 2 is a top plan view of the same; and Fig. 3 is a detail elevation of the basket like structure which is mounted upon the end of the barrel of the pistol showing the ball placed therein, in dotted lines.

Referring more particularly to the drawings, 1 designates the stock or handle of the 45 toy pistol which has a barrel 2 formed integrally therewith and extending outwardly from the handle 1 as is common in the construction of devices of this nature. The handle or stock 1 has a shoulder 3 formed 50 thereupon at the junction of the barrel 2 and the handle, which shoulder is provided with an opening 4 extending therethrough.

The opening 4 has a trigger 5 mounted 55 therein and pivotally connected to the handle or stock 1 of the pistol by means of a pin 6 which extends laterally through the

stock 1. The trigger 5 has its lower end 7 provided with a concave and a convex surface so as to be easily gripped by one of the fingers of a hand for the operating of the same and it also has a rubber band 8 thereabout and about a pin 9 which is mounted in the under surface of the stock 1 of the pistol. The trigger 5 preferably has a cut out portion formed in one edge 65 thereof for the reception of the rubber band so as to prevent the same from slipping or springing off the trigger. The rubber band 8 tends to hold the trigger in the position shown in Fig. 1 of the drawings at all times 70 and causes it to assume this position immediately after it has been operated.

The upper end 10 of the trigger 5 which serves practically the purpose of the hammer of an ordinary pistol is provided with 75 a notch 11 formed therein. The shoulder 12 which is formed by the cutting of the notch 11 normally engages the shoulder 14 which is formed where the two arms 15 and 16 of the wire 17 are bent toward and 80 twisted one about the other. The wire 17 has a circular shaped loop 18 formed upon its outer end, which is disposed directly above the handle or stock 1 of the pistol and which is formed at the termination of the 85 twisted portion 19 of the wire 17. The loop 18 is provided for the reception of a ball or similar article 20 which is to be thrown into the air by the operation of the pistol.

The wire 17 extends longitudinally along the barrel of the pistol being spaced slightly above the edge of the same and the two arms 15 and 16 are coiled about a pin 21 which is inserted through the barrel 2 near the outer 95 end of the same. The ends 22 and 23 of the wire which are left after the arms 15 and 16 are coiled about the pin 21 extend rearwardly along the sides of the pistol barrel and are securely attached to the same by 100 means of pins 24 and 25.

By coiling the wire 17 about the pin 21 a spring action is imparted to the same which will, when the trigger 5 is moved upon its pivotal pin 6 so that the shoulder 12 will 105 move out of engagement with the shoulder 14, cause the wire to spring upwardly in the direction indicated by the arrow A, and throw the ball or other article 20 high into the air. The rubber band 8 will then draw the trigger 5 to its normal position and when the wire is forced downwardly, cause the

shoulder 12 to engage the shoulder 14 and hold the pistol in a position preparatory to discharging the ball or article 20 from it.

A basket 30 which is constructed of wires whose ends are bent inwardly and coincide one with the other is mounted upon the outer end of the barrel 2 of the pistol. The ends of the wires which are bent or curved inwardly are inserted into the end of the barrel and thus the basket 30 is securely connected to the same. The basket 30 is provided for the purpose of catching the ball or article 20 as the same descends after having been thrown into the air by the spring action of the wire 17. Should it be desired, any type of spring may be employed in place of the rubber band 8 and the pistol barrel may be formed either square, round or hexagonal, these features being optional to the person manufacturing the device.

From the foregoing description taken in connection with the accompanying drawings the advantages of the construction and of the method of operation of the improved toy pistol will be readily apparent to those skilled in the art to which this invention appertains and, while in foregoing description, the principle of the operation of this inven-

tion has been described together with various features of construction, it is to be understood that certain minor features of construction, combination and arrangement of parts may be altered to suit practical conditions provided such alterations are comprehended within the scope of what is claimed. 35

What is claimed is:

A toy pistol comprising, a stock, a barrel, a trigger pivotally mounted within the stock, projecting means operatively mounted upon the barrel, said projecting means 40 consisting of a single piece of spring wire bent upon itself and having two parallel arms thereof, twisted one upon the other to form a loop for the reception of a projectile, said trigger engaging the projecting member at its twisted portion, the arms of the projecting means embracing the barrel and each being coiled upon a pin, the free ends thereof being rigidly secured to the barrel.

In testimony whereof I affix my signature 50 in presence of two witnesses.

HARRY A. GOULD.
